NECKTIE HOLDER

Dorothy B. Kauffman, Cleveland, Ohio

Application October 16, 1947, Serial No. 141,938

Term of patent 14 years

(Cl. D33—8)

To all whom it may concern:

Be it known, that I, Dorothy B. Kauffman, a citizen of the United States, residing in Cleveland, in the county of Cuyahoga, State of Ohio, have invented a new, original, and ornamental Design for a Necktie Holder, of which the following is a specification, reference being had to the accompanying drawing, forming a part thereof.

In the drawing:

Fig. 1 is a front perspective view of the necktie holder, showing my new design;

Fig. 2 is a plan view of the necktie holder; and

Fig. 3 is a view of a cross-section taken along the line 3—3 of Fig. 2.

I claim:

The ornamental design for a necktie holder, substantially as shown.

DOROTHY B. KAUFFMAN.
